UNITED STATES PATENT OFFICE.

WILHELM F. TRUELSEN, OF MILWAUKEE, WISCONSIN, ASSIGNOR TO LOGEMANN BROTHERS COMPANY, OF MILWAUKEE, WISCONSIN, A CORPORATION OF WISCONSIN.

BALING-PRESS.

No. 851,714.

Specification of Letters Patent.

Patented April 30, 1907.

Application filed November 1, 1906. Serial No. 341,516.

To all whom it may concern:

Be it known that I, WILHELM F. TRUELSEN, a citizen of the United States, residing at Milwaukee, county of Milwaukee, and 5 State of Wisconsin, have invented new and useful Improvements in Baling-Presses, of which the following is a specification.

My invention relates to improvements in presses with especial reference to that class 10 of presses known as baling presses.

The object of my invention is to provide a form of press in which the power may be applied to the platen from a single screw through lifting arms or toggle levers which 15 are pivotally connected and fulcrumed upon each other, but unconnected with the platen, and therefore free to travel along its under surface, whereby the lateral pressure of each lever upon its fulcrum or pivot pin is transmitted to the other lever and assists in lifting 20 it and whereby the platen is left free to adjust itself to the material within reasonable limits, and cramping and binding upon the lever connections is wholly avoided all parts 25 of the structure being balanced.

In the following description reference is had to the accompanying drawings in which

Figure 1 is a side view of my invention with a portion of the platen broken away. 30 Fig. 2 is a plan view of the actuating connections. Fig. 3 is a sectional view of the platen drawn on line X—X of Fig. 1.

Like parts are identified by the same reference characters throughout the several views. 35 The press box 1 is supported by frame bars 2 and provided with a suitable door 3 for the removal of the bale. A head piece 4 is loosely connected with the upper end portions of the frame posts and a loose platen 5 40 is guided by the frame bars and an auxiliary guide member 6. The platen 5 is preferably provided with a marginal depending web 10 which carry guide rollers 11.

The platen is actuated from a screw shaft 45 12 which is centrally supported in suitable journals 13 from a bed 14 and screw threaded right and left at 15 and 16 respectively. Motion is transmitted from the screw shaft to the platen through the traveling members, 50 (comprising nuts 17 and 18), and crossed levers 19 and 20 which are pivoted to the respective nuts and also to each other at the crossing point 21 and provided with rollers

22 bearing on the under surface of the platen. 55 When the screw is turned in one direction, the nuts 17 and 18 approach each other, and the levers are thereby drawn toward each other at their lower ends and the upper ends correspondingly lifted and forced toward each other along the under surface of the 60 platen, the platen being lifted upon the upper ends of the levers, each of which swings upon the pivot pin 21. This pin is supported by each lever and serves as a fulcrum for both. In the construction illustrated there 65 are two levers 19 connected respectively to the opposite sides of the nut 17 and two levers 20 similarly connected to the nut 18; rollers 23 are employed to support the levers from the bed 14 and relieve strain on the 70 nuts. A single pivot pin or bolt 21 serves for the four levers at the crossing point, all the levers being therefore required to move in unison.

It will be observed that the levers 19 and 75 20 are arranged in pairs, the two levers 19 being pivoted to studs projecting from the nuts at diametrically opposite points, preferably substantially in the horizontal plane of the screw axis, so that the pressure is balanced on the screw threads. It will also be observed that the levers 19 and 20 on either side of the screw are offset in opposite directions to receive the pivot pin 21, so that the 80 respective ends of the levers are in a line parallel with the screw, thus making a perfectly balanced structure. The rollers 22 are not mounted directly upon the levers, but at the outer sides thereof upon a roller supporting 85 cross rod, which also connects the otherwise free ends of the pair of levers 19, (or 20), and thus gives steadiness to the structure.

Having thus described my invention what I claim as new and desire to secure by Letters Patent, is,

1. In a press of the described class, the combination with a platen, an operating screw centrally located in suitable stationary bearings underneath the platen with its respective end portions screw threaded right and left, traveling nuts mounted on the respective end portions of said screw, a pair of levers for each of the nuts, pivotally secured to opposite sides thereof,—the levers of each pair being crossed with those of the other 105 pair, and pivoted thereto, said platen being

mounted loosely upon the ends of said levers beyond the crossing point, and supported therefrom.

2. In a press of the described class, the combination of two pairs of levers, those of each pair being connected by traveling members at their lower ends, and by cross rods at their upper ends, rollers mounted on the cross rods, a platen loosely mounted on the rollers, an actuating screw mounted in stationary bearings and extending through the traveling members between the levers, said screw having right hand threaded engagement with one of the traveling members and left hand threaded engagement with the other.

3. In a press of the described class, the combination of two pairs of levers, those of each pair being connected by traveling members at their lower ends, and by cross rods at their upper ends rollers mounted on the cross rods, a platen loosely mounted on the rollers, an actuating screw mounted in stationary bearings and extending through the traveling members between the levers, said screw having right hand threaded engagement with one of the traveling members and left hand threaded engagement with the other,—the levers of each pair being crossed with those of the other, and pivoted thereto at an intermediate point.

4. In a press of the described class, the combination of two pairs of levers, those of each pair being connected by traveling members at their lower ends, and by cross rods at their upper ends, rollers mounted on the cross rods, a platen loosely mounted on the rollers, an actuating screw mounted in stationary bearings and extending through the traveling members between the levers, said screw having right hand threaded engagement with one of the traveling members and left hand threaded engagement with the other,—the levers of each pair being crossed with those of the other, and pivoted thereto at an intermediate point by a common pivot bolt connecting the four levers.

5. In a press of the described class, the combination of two pairs of levers, those of each pair being connected by traveling members at their lower ends, and by cross rods at their upper ends, rollers mounted on the cross rods, a platen loosely mounted on the rollers, an actuating screw mounted in stationary bearings and extending through the traveling

members between the levers, said screw having right hand threaded engagement with one of the traveling members and left hand threaded engagement with the other,—the levers of each pair being crossed with those of the other, and pivoted thereto at an intermediate point, and said levers and platen supporting rollers being symmetrically arranged to balance the pressure upon the platen and the adjusting screw.

6. In a press of the described class, the combination of two pairs of levers, those of each pair being connected by traveling members at their lower ends, and by cross rods at their upper ends, rollers mounted on the cross rods, a platen loosely mounted on the rollers, an actuating screw mounted in stationary bearings and extending through the traveling members between the levers, said screw having right hand threaded engagement with one of the traveling members and left hand threaded engagement with the other, the levers of each pair being crossed with those of the other, and pivoted thereto at an intermediate point, and said levers being offset at the intermediate pivot point and arranged with their outer end portions equidistant from the vertical plane of the screw, and that of the intermediate pivot bolt.

7. In a press of the described class, the combination of two pairs of levers, those of each pair being connected by traveling members at their lower ends, and by cross rods at their upper ends, rollers mounted on the cross rods, a platen loosely mounted on the rollers, an actuating screw mounted in stationary bearings and extending through the traveling members between the levers, said screw having right hand threaded engagement with one of the traveling members and left hand threaded engagement with the other, the levers of each pair being crossed with those of the other, and pivoted thereto at an intermediate point and said rollers being located on the outer ends of their corresponding connecting rods and equidistant from the vertical planes of the screw, and intermediate pivot bolt respectively.

In testimony whereof I affix my signature in the presence of two witnesses.

WILHELM F. TRUELSEN.
